UNITED STATES PATENT OFFICE.

JOHN B. REESE, OF RENO TOWNSHIP, LEAVENWORTH COUNTY, AND PHILLIP C. STRAHL AND
MORTON M. ADAMS, OF LAWRENCE, KANSAS.

GRAVE MARKER AND PROTECTOR.

No. 868,810.

Specification of Letters Patent.

Patented Oct. 22, 1907.

Application filed April 2, 1907. Serial No. 366,058.

To all whom it may concern:

Be it known that we, JOHN B. REESE, a citizen of the United States, residing in Reno township, Leavenworth county, State of Kansas, and PHILLIP C. STRAHL and MORTON M. ADAMS, citizens of the United States, residing at Lawrence, in the county of Douglas and State of Kansas, have invented certain new and useful Improvements in Grave Markers and Protectors, of which the following is a specification.

10 This invention relates to artificial stone grave markers and protectors and our object is to produce a structure of this character which will stand as a permanent monument to the memory of the deceased over whose grave it is placed, that is to say our object 15 is to produce a structure which will prevent the coffin from being washed out of the grave by flood and will also prevent the body from being readily removed from the grave without the construction of a tunnel, which is a method too slow and laborious to be practiced by unauthorized persons.

With this object in view and others as hereinafter appear, the invention consists in certain novel and peculiar features of construction and organization as hereinafter described and claimed; and in order that 25 it may be fully understood reference is to be had to the accompanying drawing, in which—

Figure 1, is a perspective view of a section of a family burial plot showing one grave ready to receive the coffin, a second after it has been sealed and a third 30 after it has been completed. Fig. 2, is an enlarged vertical section on the line II—II of Fig. 1. Fig. 3, is a longitudinal section on the line III—III of Fig. 1.

In the said drawings, 1 indicates a cement curbing which may mark the boundaries of the burial plot or 35 of a particular part thereof destined to receive a predetermined number of graves, said curbing extending down into the ground a sufficient distance to prevent undermining by a flow of water.

2 indicates a similar curbing surrounding each grave 40 3, which curbing may extend completely around the grave but preferably will extend only around three sides of the same leaving the fourth side or end to be formed by the boundary curbing 1 and where two graves are arranged side by side, the intervening side 45 of the curbing will form a part of the marker and protector of each, it being desirable in this case that such intervening side numbered 4, shall preferably be of greater width than a side 5, which is not situated between two graves. The length and width of the 50 grave is preferably less than their surrounding curbings and within said curbings the surface of the ground

is lowered as at 6 preferably a few inches below that of the natural surface.

After a coffin has been deposited in the grave when completed to the extent shown at the left hand side 55 of Fig. 1 and the grave filled in in the usual manner, a cement slab 7 is constructed over the grave, the upper surface of said slab preferably corresponding to that of the curbing 1 and 2, and said slab is preferably provided with short depending walls 8, which rest upon 60 the lowered surface 6 of the earth within the curbing said slab being stiffened and strengthened by reinforce bars 9 or in any other suitable manner, it being understood that the preferred construction is to construct the cement slab in the position which it occupies so that it will unite as an integral mass with the curbings, it being also understood that if desired the curbings can be molded at the same time and therefore after the coffin has been deposited in the grave.

To protect the grave more thoroughly and at the 70 same time provide a monument of more or less ornamental appearance, a cement cap-stone 10 of several tons weight by preference and of any desired configuration is mounted upon the cement slab, said cap stone by preference being molded upon and at the 75 same time as said slab, in order that it may form an integral mass with the latter. The cap stone may bear the desired inscription or may be adapted to receive an inscription plate, or said cap stone may form a convenient support or base for an ornamental or 80 symbolical figure, urn or other ornament for the grave.

The curbings are provided with grooves or gutters 11 for carrying off water falling upon the structure and discharging it externally of the plot.

From the above description it will be apparent that 85 we have produced a grave marker and protector possessing the features of advantage enumerated as desirable and we wish it to be understood that we do not desire to be restricted to the exact details of construction shown and described as obvious modifications 90 will suggest themselves to one skilled in the art.

Having thus described the invention what we claim as new and desire to secure by Letters Patent, is:—

1. A grave marker and protector, comprising a curbing 95 set into and projecting above the ground around the mouth of the grave, a slab united to the curbing with a water-tight relation and bridging the grave, and a cap-stone upon and permanently united to the slab and bearing a water-tight relation thereto.

2. A grave marker and protector, comprising a curbing surrounding the grave and projecting above the ground and of greater width and length than the grave, a slab 100

fitting within and against and bearing a water tight relation to the curbing and having its upper side flush with the corresponding surface of the latter and provided with depending walls resting upon the ground around the grave within the curbing and terminating at a point below the natural plane or level of the earth, and a cap stone superposed with respect to said slab.

3. A grave marker and protector comprising a curbing surrounding the grave and projecting above the ground and of greater width and length than the grave and provided in its upper side with gutters to conduct surface water to the outer side of the curbing, a slab fitting within and against and bearing a water tight relation to the curbing and having its upper side flush with the corresponding surface of the latter and provided with depending walls resting upon the ground around the grave

and within the curbing and terminating at a point below the natural plane or level of the earth, and a cap stone superposed with respect to said slab.

In testimony whereof we affix our signatures, in the 20 presence of two witnesses.
